BAG

George W. Poppe, Brooklyn, N. Y., assignor to
 Equitable Paper Bag Co. Inc., Long Island City,
 N. Y., a corporation of New York

Application December 3, 1943, Serial No. 512,704

1 Claim. (Cl. 229—57)

This invention relates to bags.

An object of this invention is a bellows-fold flat-bottom type bag which is substantially sift-proof.

A bag embodying the invention consists of a bellows-fold tube having a front wall and a back wall with one of said walls (preferably the back wall), and the bellows folds being shaped to provide a lip at the top edge of the tube and a recess at the bottom edge of the tube through which is exposed a portion of the inner face of the other wall. The lower end of the tube is folded at about a line transverse of the tube to bring the outer face of the lower end of said one wall and the exposed inner face portion of said other wall into contact with the outer face of said one wall. The folded portion of the tube is longer than the depth of the bellows fold so as to form a flat bag bottom and extends beyond the bottom edge a short distance along said one wall. Adhesive is applied between said one wall and the folded-over tube portion beyond the bag bottom edge to interjoin them. This arrangement provides a substantially sift-proof bottom for the bag.

Bags embodying this invention can be made on standard bag-making machines with only slight adjustment of such machines. They can, therefore, be made at a much higher speed and lower cost than other bags of the sift-proof bottom type which, heretofore, have had to be manufactured on machines having a low production rate.

Other objects, novel features and advantages of this invention will become apparent from the following specification and accompanying drawing, wherein:

Fig. 1 illustrates a tube from which the bag is made;

Fig. 2 is a perspective view of the completed bag in a partially open condition, and

Fig. 3 is a perspective view of the bag in fully open condition.

Referring to Fig. 1, the tube 10 has a front wall 11, a seam wall 12 and bellows fold 13. This tube is formed from a web in the well-known manner with the two edges of the web being joined together by adhesive at 14 to form a usual

seam. The tube is formed to provide a lip 15 at the top edge of the wall 12 and bellows fold 13 and a corresponding recess at the bottom edge whereby a portion of the inner surface of the wall 11 is exposed. While the tube has been shown as of the center seam type, the tube may equally well have its seam other than central.

The bottom end of the tube is folded about a transverse line 16 more removed from the apex 10 of the wall 12 recess than the depth of the bellows fold 13 to bring the bottom portion of the wall 12 and the exposed portion of the wall 11 into contact with the wall 12 to form a flat bottom bag and adhesive is applied between the contacting walls as indicated at 17. The adhesive joins the lower edges of the bellows 13 to the walls 11 and 12 and also joins the exposed portion of the inner surface of the wall 11 to the outer surface of the wall 12 as well as joins the folded-up portion of the wall 12 to the remainder of the wall 12.

The line 16 is so arranged that the folded-over portion of the walls 11 and 12 are longer than the distance from the line 16 to the edge of the bag bottom. These portions, therefore, continue around the bottom corner of the bag and part way up the side wall 12. This arrangement provides a sift-tight seam along each edge of the bottom and effectively prevents loss of contents from the bag.

I claim:

A bag consisting of a bellows fold tube having a front wall and a back wall, said bellows folds and one of said walls being formed at the top edge with lips and at the bottom edge with corresponding recesses exposing a portion of the inner surface of the remaining wall, said tube being folded at one end about a line transverse thereof more removed from the apex of said wall recess than the depth of the bellows fold into contact with said one wall to form a flat bag bottom when the tube is open with a portion of the tube extending beyond, and adhesive applied between said one wall and that portion of said tube extending beyond the edge of the bag bottom.

GEORGE W. POPPE.
